UNITED STATES PATENT OFFICE.

JOHN R. SMITH, OF ROCHESTER, NEW YORK.

MIDDLING-PURIFIER.

SPECIFICATION forming part of Letters Patent No. 271,932, dated February 6, 1883.

Application filed June 12, 1882. (No model.)

To all whom it may concern:

Be it known that I, JOHN R. SMITH, of Rochester, New York, have invented certain new and useful Improvements in Middlings-Purifiers; and I do hereby declare the following to be a full, clear, and exact description of the invention, such as will enable others skilled in the art to which it appertains to make and use the same, reference being had to the accompanying drawings.

The object of this invention is to improve the machines known as "middlings-purifiers," and it consists in such construction of parts that the middlings-granules, after passing through the shaker-bolt, will of themselves keep the meshes of the cloth clear without the aid of a brush, roller, or jarring device, as will be fully hereinafter described.

In the drawings, Figure 1 represents a broken side view of the half-length of a middlings-purifier, from the top of the shaker-frame down, to include the showing of the devices which clean the cloth and the means for operating such devices. Fig. 2 represents a top plan view of the cleaning devices, and Fig. 3 represents a broken transverse view of Fig. 1.

The framing and casing that supports and surrounds the improvement is not shown in the drawings or described in this specification, as the devices of this improvement can be placed underneath any of the well-known machines for purifying middlings where a shaking-bolt is used.

A represents the broken side of a shaker-frame, constructed and hung in the machine in the usual way, having the bolt-cloth A' secured to its under side.

B B are transverse, horizontal, and reciprocating carriers of middlings-granules, having a concave groove, b, longitudinally in their top edges, which do not at any time extend high enough to touch the bolt-cloth A'. The carriers B are rigidly secured in position by the cross-braces b' b' and longitudinal reach b'.

C C' are transverse shafts, freely revolving in proper bearings, secured to the sides of the machine by brackets C'' or by other well-known means. Shaft C is located at or near the center of the length of the machine, and extends entirely across the machine and outside thereof at one or both sides, so as to attach a driving pulley or pulleys to revolve the shaft from

any convenient revolving pulley or from any power to revolve it. Shafts C' are short shafts, located near to one end of the machine, and to revolve in proper bearings upon or attached to brackets C'', as seen in Fig. 3.

D D are pairs of sprocket-wheels fast upon the shafts C and C', equidistant from the longitudinal centers of the carriers B.

D' D' are endless chains around the sprocket-wheels D, the open links of which take over the projecting teeth on the said sprocket-wheels, and are made to travel in the direction shown by the arrows in Fig. 1.

d is a metal rod, secured at each of its ends to the endless chains D' and at right angles thereto.

E is a downwardly-projecting lug from the longitudinal brace or reach b'', or to any other convenient part of the reciprocating frame which actuates the carriers B, and extends down so as to always reciprocate over the shaft C without touching it. E' is another downwardly-projecting lug, located in the rear of E and at the end of the frame which reciprocates the carriers B, projecting down below the lower line of the under peripheries of the sprocket-wheels D, as seen in Fig. 1.

The frame that supports and keeps the carriers B in their parallel relation must be sufficiently strong to prevent any displacement of parts, so as to bind, and yet be light, so as to prevent friction as much as is possible, as the carriers B at each end have a groove, f, therein to slide on guideways F, that are secured to the sides of the machine; hence the necessity for keeping the carriers perfectly parallel at all times.

This improvement constructed as described and placed at the proper distance below the reciprocating shaker of a middlings-purifier, motion being applied to shaft C, and the sprocket-wheels put in revolution, causing the endless chains to travel in the direction shown by arrows, the cross-bar d engages the lug E and forces it forward, carrying with it the granules-carriers B, forcing the lug E beyond the sprocket-wheels on shaft C, or so that the bar d will pass around the sprockets, leaving the lug free, when the carriers B will for a moment be inactive or at rest until the bar d has passed over and around the sprockets and is on its return, when it engages the longer pro-

jecting lug, E', that has passed between the two short shafts C' C', and thereby forces the carriers B back to the position that they started from, as seen in Fig. 1. The shaft C and its 5 sprocket-wheels being at or near to the center of the length of the machine, and the carriers shown to reach but about half the length, yet when the carriers B are reciprocated the full extent of their throw the carrier, which is seen 10 over shaft C in Fig. 1, will be forced forward to the extreme end of the bolt-cloth on the shaker. Thus the whole length of the bolt-cloth will be traversed by the carriers, although but about half the length of the bolt-cloth is 15 shown. As the carriers B reciprocate underneath and out of contact with the bolt-cloth A', and are of considerable width on their top surfaces and made concave, the middlings x, which pass through the bolt-cloth A', will fall 20 into the concave grooves b, and pile up until they reach the bolt-cloth on the shaker-frame, and when the granules of middlings are in contact with the cloth and the carriers in reciprocation back and forward they present nothing but the loose and unconfined granules of 25 middlings against the under side of the bolt-cloth, and this action will cause the granules to roll and tumble about in contact with the fibers of the bolt-cloth, which action will keep 30 the meshes of the cloth open, and at the same time the cloth keeps the granules of middlings from too great accumulation in the concaves of the carriers, so that both the bolt-cloth and

the carriers are mutually and automatically keeping each other in proper order, and this 35 is all performed without the aid of brushes, rollers, jarring-off devices, or any other agent than the granules of middlings themselves to keep the meshes of the cloth open and without perceptible wear upon the cloth, and is of 40 advantage to the middlings, as the friction obtained upon the granules of middlings forces off all the fine adhering dust of flour not before removed.

In this application I have not described any 45 of the operations of a middlings-purifier except such parts as I claim as my invention, and I propose to connect such described improvements with or to any ordinary middlings-purifier.

I claim—

1. The combination, with the bolt-cloth A' 50 of the shaker of a middlings-purifier, of the reciprocating granules-carrier B, having a concave groove in its top surface and means to reciprocate it, substantially as and for the purposes described.

2. In a machine, as above described, the combination, with the bolt-cloth of a shaker, of devices by which the bolt-cloth of the shaker is 55 kept clean by the action of the granules of middlings after passing through the cloth and in contact therewith, substantially as described.

JOHN R. SMITH.
